CLAIM

The ornamental design for a yoga mat, as shown and described.

DESCRIPTION

FIG. 1 is a top plan view of a yoga mat showing my new design;

FIG. 2 is a perspective view thereof; and,

FIG. 3 is a perspective view thereof, showing a person stretching on the yoga mat.

The broken line showing text, person, and accessories is included for the purpose of illustrating environmental structure and forms no part of the claimed design.

1 Claim, 3 Drawing Sheets

FIG. 3
